UNITED STATES PATENT OFFICE.

DANIEL E. LESSER, OF WARREN, PENNSYLVANIA, ASSIGNOR OF ONE-THIRD
TO PHILLIP G. WHEELER, OF SAME PLACE.

TROLLEY-POLE RETRIEVER.

SPECIFICATION forming part of Letters Patent No. 631,854, dated August 29, 1899.

Application filed June 15, 1898. Serial No. 683,489. (No model.)

To all whom it may concern:

Be it known that I, DANIEL E. LESSER, a citizen of the United States, residing at Warren, in the county of Warren and State of Pennsylvania, have invented a new and useful Trolley-Pole Retriever for Electric-Railway Cars, of which the following is a specification.

My invention relates to means for retrieving the trolley-pole of electric-railway cars which commonly employ a trolley having underrunning contact with an overhead electric conductor and normally pressed upward by a spring which when the trolley slips off the conductor by crossing switches or splices in the wire throws the pole to a position where the trolley or the pole or the cross-wires which support the conductor are liable to be broken, particularly when the car is running at a comparatively high speed.

The object that I have in view is to provide a simple and inexpensive construction embracing a few parts which shall present a neat appearance on the car, secure precision and certainty of operation, and amplify the extent of vertical play of the pole cord or cable to render the trolley adaptable to overhead conductors which may be at variable distances from the track or the car adapted thereto.

With these ends in view my invention consists in the peculiar construction and arrangement of parts, which will be hereinafter fully described and claimed.

To enable others to understand the invention, I have illustrated the same in the accompanying drawings, forming a part of this specification, and in which—

Figure 1 is an elevation of a portion of an electric-railway car equipped with an under-running-trolley for contact with an overhead conductor and showing my retrieving device in operative relation to the car and pole. Fig. 2 is an elevation, on an enlarged scale, of the retrieving device. Fig. 3 is a vertical sectional view of the device shown by Fig. 2. Fig. 4 is a transverse section on the plane indicated by the dotted line 4 4 of Fig. 3.

Like numerals of reference denote like and corresponding parts in each of the several figures of the drawings.

1 designates a portion of a car; 2, the frag-

ment of an overhead electric conductor; 3, the trolley-pole, which is mounted in an ordinary way on the car and is combined with springs which tend to normally force said pole in an upward direction, and 4 is the trolley-wheel, which is mounted in the pole 3 to have underrunning contact with the elevated conductor. All these parts are ordinary in the art, and with the pole I have combined a retrieving device which tends to counteract the sudden upward movement of the pole under the influence of the springs when the trolley slips off the conductor due to the obstruction offered by the switches, turnouts, crossings, or splices in the conductor.

In the practical service of ordinary electric-railway cars it is found that the cross-wires which support the feed-conductor are liable to be broken by the pole or trolley striking against the cross-wires when the trolley slips off the conductor, especially when the car is traveling at a comparatively high speed, and frequently the trolley-wheel or the pole become broken, as well as the cross supporting wires. The aim of my invention is to provide a simple and inexpensive device for retrieving the pole and trolley in the event of disengagement of the trolley from the conductor, and this retrieving mechanism embodies a drop-weight which is normally held inactive by a trip-pawl that is automatically disengaged from the drop-weight on the upward movement of the trolley-pole, thereby releasing the drop-weight and permitting it to counteract the upward pressure of the springs acting against the trolley-pole.

My improved retriever is illustrated more particularly by Figs. 2 and 3 of the drawings, attention to which is now invited. This retriever consists in part of a vertical hollow guide-standard 6, which is externally threaded at its lower end for the purpose of screwing it into a threaded socket of a foot-block 7. This foot-block may be fastened on a car not having a bumper by bolts 8, adapted to pass through a flange of the foot-block and into a part of the car; but I do not desire to restrict myself to fastening the guide-standard to the foot-block, because it may be attached to the car-bumper, or it may be applied against one side or end of the car-body, for which last

named purpose the hollow standard may be formed with a longitudinal flattened side 9. (See Fig. 4.) This construction of the standard provides for the firm and secure application thereof to the end of a car substantially below the roof or deck thereof, and the standard may be bolted firmly to the car to occupy the position shown by Fig. 1. The upper open end of the hollow standard is externally threaded for the reception of a flanged internally-threaded cap 10, which is screwed to the upper end of the standard for the purpose of excluding rain and dust from entering the standard and interfering with the free sliding movement of the drop-weight therein. This cap is detachable readily from the hollow standard for access to the drop-weight.

The drop-weight 11 is elongated and of sufficient heaviness or ponderosity to counteract the springs that normally elevate the trolley-pole for the trolley-wheel to have contact with the conductor, and this elongated drop-weight is provided with a laterally-extending arm 12, to which is connected a cable or cord 13, provided for the adjustment and control of the trolley-pole.

The arm 12 is secured rigidly to the drop-weight, and it passes through a longitudinal slot 14, which is formed in one side of the hollow guide-spindle, said slot being of sufficient length to insure the necessary vertical play of the drop-weight. The arm 12 is thus arranged to protrude and be exposed outside of the standard, thus enabling the operating cable or cord to be readily attached thereto, and this arm serves as a guide to direct the drop-weight in its vertical travel and present the notch 15 of the drop-weight in proper position for engagement by the holding-dog. The notch 15 is formed in the side of the drop-weight opposite to the slot 14 in the guide-standard, and this notch has an inclined face which terminates in an abrupt shoulder 16, that lies at right angles to the longitudinal axis of said weight 11.

The dog 18 is arranged exteriorly on the guide-standard, and it is supported by a clamp or band 19. This band is fitted around the guide-standard at or above the upper terminal of the slot 14 therein, and this band or clamp has its ends extended to form short arms, between which the holding-dog is adjusted and that receive the pivotal bolt 20, which supports the dog in the clamp or band. The dog is pivotally mounted at a point intermediate of its length in the band or clamp, and the lower end of said dog is weighted, as at 21, to throw its nose 22 away from the notched face of the drop-weight when the dog is released therefrom. The nose 22 of the dog is adapted to pass through a short slot 17, which is formed in the standard 6 diametrically opposite to the longitudinal slot 14 therein, and when the drop-weight is elevated to bring the notch 15 opposite to or coincident with the slot 17 of the standard the weighted end of the dog may be drawn outwardly by hand to force

the nose 22 through the slot 17 and into the notch 15 for said nose to engage with the shoulder 16, thereby operatively connecting the counterbalanced dog with the drop-weight to sustain the latter in its raised position.

The operating cable or cord 13 may be fastened securely to the protruding end of the arm 12 and the drop-weight, but to enable the retrieving device to afford greater amplitude in the vertical adjustment of the trolley-pole, and thus adapt the latter to support the trolley-wheel in operative relation to overhead conductors which may lie at variable distances from the track, I prefer to employ the guide-sheave 23 in connection with a cord or cable which passes under the guide-sheave and is extended upwardly to the cap 10 or the upper end of the hollow standard. This guide-sheave 23 is mounted in a suitable way on the protruding end of the drop-weight arm 12, and the cord or cable 13 is extended beneath the guide-sheave and is fastened, as at 24, to the cap 10 on the upper part of the standard 6. The employment of this guide-sheave enables a longer cable or cord 13 to be used than when said cable or cord is attached directly to the arm 12.

In the practical service of my improvement in connection with an electric-railway car the hollow standard 6 is secured in a vertical position either to the end or to one side of the car, and the cable 13 is attached to the trolley-pole and suitably connected either to the drop-weight arm 12 or fitted beneath the guide-sheave 23 on the said arm. To adjust the retriever for service, the cord is manipulated by hand to elevate the drop-weight until the notch 15 thereof is coincident with the short slot 17 of the standard, and the holding-dog is then adjusted by hand for its nose to engage the shoulder 16. There is a permanent allowance for abundant slack in the cable 13 between its attachment to its arm 12 in the trolley-pole for the latter to have a limited vertical play without affecting the drop-weight. In the event of the trolley-wheel slipping off the overhead conductor the springs tend to quickly elevate the pole and trolley to a vertical position; but this sudden upward movement of the trolley-pole strains the cable or cord 13 in an upward direction, thus raising the drop-weight sufficiently for the nose of the holding-dog to disengage with the shoulder 16, whereupon the weighted end of the dog retracts the nose thereof from the slot 17 of the hollow standard. The drop-weight is now free to descend in the hollow standard, and it is of sufficient weight to counteract the impelling force of the springs which control the trolley-pole, thereby positively depressing the trolley-pole and the trolley-wheel and holding the parts out of the path of the cross-wires which support the feed-conductor.

Slight changes may be made in the form of some of the parts, while their essential features are retained and the spirit of the invention embodied. Hence I do not desire to

be limited to the precise form of all the parts as shown, reserving the right to vary therefrom.

Having thus described the invention, what 5 I claim is—

A trolley-pole retriever comprising a standard having a short slot in one side and a long slot in the opposite side, a shouldered weight within said standard, the arm, 12, fixed to the 10 weight to play in the long standard-slot and carrying a guide-sheave, 23, the cord, 13, fastened at one end to the standard at a point above the upward limit of travel of the weight and passing beneath the guide-sheave and

from thence attached to a trolley-pole to provide a permanent allowance of slack, a supporting-band clamped to the standard, and a balanced detent pivoted in said band for its nose to play in the short standard-slot and engage with the shouldered weight, substantially as described. 15 20

In testimony that I claim the foregoing as my own I have hereto affixed my signature in the presence of two witnesses.

DANIEL E. LESSER.
